UNITED STATES PATENT OFFICE.

WALTER A. JONES, OF COLUMBUS, OHIO.

COOLING DEVICE FOR GLASS-DRAWING APPARATUS.

1,396,216.

Specification of Letters Patent.

Patented Nov. 8, 1921.

Application filed October 19, 1918. Serial No. 258,783.

To all whom it may concern:

Be it known that I, WALTER A. JONES, a citizen of the United States, residing at Columbus, in the county of Franklin and State 5 of Ohio, have invented new and useful Improvements in Cooling Devices for Glass-Drawing Apparatus, of which the following is a specification.

This invention is an improved device for 10 cooling glass cylinders contiguous to the molten glass during the drawing operation.

In drawing glass cylinders it is well understood that the drawing operation is greatly facilitated if the glass forming the 15 cylinder is more or less chilled immediately after leaving the molten bath, and many different types of cooling devices have been produced for this purpose. Such devices as are now in general use are objectionable because of their clumsiness which makes 20 them rather difficult to handle, involving considerable labor and loss of time in removing them and replacing them after each draw. One of the objects of the invention 25 is to provide a water cooled ring of sectional construction which may be readily placed into and removed from operative position. A further object is to provide a top stone having means for supporting the cooling 30 device, whereby the latter may be raised or lowered with the top stone. A further object is to provide improved means whereby the device may be readily moved to an inoperative 35 position when not required.

The invention will be hereinafter fully set forth and particularly pointed out in the claims.

In the accompanying drawing:

Figure 1 is a perspective view illustrating 40 a top stone and a water cooled ring constructed in accordance with the invention, the ring being in operative position. Fig. 2 is a similar view, illustrating the ring moved to inoperative position and the drawing 45 opening closed. Fig. 3 is a transverse sectional view.

Referring to the drawing, 10 designates a top stone of any suitable type, preferably constructed of refractory clay, and provided 50 with the drawing opening 11. Secured to the top stone in suitable manner are hangers 12, each formed of uprights rigidly secured to the top stone, and connected by a horizontal bar, said hangers being engaged 55 by the hook portions of the top stone suspension rods 13, suspended from any suit-

able hoisting mechanism, not shown, but in a manner well understood in the art. The upright portion of the hangers 12, are provided with bearings 14, in which are mounted 60 rock shafts having solid middle portions 15 and hollow end portions 16. The cooling ring consists of two, more or less, sections 17, two of such sections being illustrated and of semi-circular form. Said sections are 65 formed with hollow bodies which communicate with the hollow portions 16 of the rock shaft, through hollow hinge members 18, the ends of which are attached to the sections 17 and the hollow shafts respectively, so that 70 the sections 17 may be swung to an upright position as shown in Fig. 2, the rock shaft rocking in the bearings 14. Flexible pipes 19, leading from a source of supply, not shown, are connected to the hollow shaft 75 portions 16, by means of suitable couplings 20. In order to assist in the movement of the ring sections 17, cables 21 are provided, connected to the rings at 22, and bearing against antifriction rollers 23, carried by the 80 hangers 12. Said cables are provided with counterweights 24, and work upon sheaves 25 supported in an elevated position.

Cooperating with the top stone 10, is a refractory clay anchor or ring 26, which 85 may be of any well known construction, the same being provided with a flange 27, which fits within the drawing opening 11. A refractory clay cover 28, is also provided to cover the drawing opening during the melting down of the aftermath, said cover being provided with hooks 29, positioned to be engaged by suspension rods, whereby it may be handled in a manner well understood in the art.

In operation, when it is desired to draw a cylinder, the anchor 26 is brought in position beneath the top stone, and the latter lowered until the flange 27 enters the drawing opening 11, thereby holding the anchor 100 in position. The sections 17 of the cooling ring are then lowered to the position illustrated in Fig. 1, whereupon the bait may be inserted, and the drawing operation proceeded with. After the cylinder has been 105 completed and it is desired to draw the same out thin so that the burning off and separation of the finished cylinder from the molten body may be brought about, the ring sections 17 are moved to the positions illustrated in Fig. 2. If it is desired to draw 110 the necks and caps of the cylinder relatively

thin with respect to the body of the cylinder, the ring sections 17 are not placed in the positions illustrated in Fig. 1 until the neck and cap have been formed, after which, and 5 without interruption to the drawing process, the ring sections may be placed in position to surround and cool the rest of the cylinder as it is being drawn. It will be understood, of course, that the cooling fluid is 10 introduced through pipes 19 at one end of each rock shaft, and passes through the contiguous hollow portion 16 and hinge 18, into the section 17, after which it passes out through the other hinge member 18, hollow 15 portion 16 and pipe 19.

From the foregoing it will be readily understood that by means of the invention the cooling effect produced may be so controlled that the necks and caps of cylinders 20 are formed in a manner which will permit of the working of the glass hot, until the necks and caps of cylinders are formed, which is a very important feature in the art 25 of drawing glass cylinders, and the cooling device is capable of such control that after the cylinder has been drawn, the cooling action may be eliminated in order that the walls of the cylinder at the juncture with the molten glass, may be drawn out very 30 thin so that the burning off and separation of the finished cylinder from the molten body may be quickly accomplished. Another 35 advantage lies in the construction and mounting of the cooling ring whereby the cooling sections may be moved to one side if thin cylinders are required. Another 40 advantage lies in mounting the cooling device upon the top stone, whereby separate handling apparatus is not required to lift them 45 independently, as is now common practice, whereby the cooling sections may be moved to one side and the refractory cover placed over the top stone during the reheating of the aftermath, the cooling ring being always maintained in operative juxtaposition with respect to the opening in the top stone.

Having thus explained the nature of the invention and described an operative manner of constructing and using the same, al- 50 though without attempting to set forth all of the forms in which it may be made, or all of the forms of its use, what is claimed is:

1. A cooling device of the character de- 55 scribed comprising a stationary support, a cooling ring formed of complemental sec- 60 tions movably mounted upon said support independently of each other, and means for supplying a cooling medium to said sections.

2. A cooling device of the character de- 65 scribed comprising a cooling ring formed of complemental sections, means for mov- 70 ably supporting the sections independently of each other, and means for supplying cool- 75 ing medium to said sections through the 80 supporting means.

3. A cooling device of the character de- 70 scribed comprising a top stone, a hollow ring section, means supporting said section on said top stone to swing on an axis to and from an operative position, means for sup- 75 plying a cooling fluid to said ring section.

4. A cooling device of the character de- 75 scribed comprising a top stone, a hollow ring section, a hinge support between said top stone and said ring section, and means 80 for supplying a cooling medium to said ring section.

5. A cooling device of the character de- 80 scribed comprising a top stone, a hollow ring section, a hinge support between said top 85 stone and said ring section, and means for supplying a cooling medium to said ring section through said hinge support.

6. A cooling device of the character de- 85 scribed comprising a top stone, a hollow ring section, hinge members attached to the ring section, a shaft mounted upon said top stone and supporting said hinge members, and means for supplying a cooling medium to said ring section.

7. An improvement in cooling devices for 90 glass drawing apparatus, a hollow ring section, hollow hinge members attached thereto and communicating with the interior thereof, and a shaft for supporting said hinge mem- 95 bers, said shaft being provided with hollow portions communicating with the hinge members.

8. As an improvement in cooling devices 100 for glass drawing apparatus, a rock shaft having hollow ends, means for supporting the rock shaft, hinge members attached to the hollow ends of said rock shaft, said hinge members being hollow and communicating with said hollow ends, and a hollow 105 ring section supported by said hinge members and in communication therewith.

9. A cooling device of the character de- 110 scribed comprising a cooling ring formed of complemental sections, hinge means for in- 115 dependently supporting said sections, and means for raising and lowering said sec- tions.

10. An improvement in cooling devices for 115 glass drawing apparatus comprising a top stone provided with a drawing opening, and a cooling ring supported by said top stone and movable in an arc toward and from 120 said drawing opening.

11. An improvement in cooling devices for 120 glass drawing apparatus comprising a top stone provided with a drawing opening, and a cooling ring formed of complemental sec- 125 tions independently supported by said top stone.

12. An improvement in cooling devices for 130 glass drawing apparatus comprising a top stone provided with a drawing opening, and a cooling ring formed of complemental sec- tions hinged to said top stone.

13. An improvement in cooling devices for glass drawing apparatus comprising a top stone provided with a drawing opening, means for suspending said top stone, and a cooling ring movably attached to and supported by said top stone. 5
14. An improvement in cooling devices for glass drawing apparatus comprising a top stone provided with a drawing opening, 10 means whereby said top stone may be suspended, and a cooling ring formed of sections movably supported by said suspending means.
15. An improvement in cooling devices for glass drawing apparatus comprising a top stone provided with a drawing opening, 15 hangers for suspending said top stone, and a cooling ring formed of complemental members supported by said hangers.
- 20 16. An improvement in cooling devices for glass drawing apparatus comprising a top stone provided with a drawing opening, rock shafts supported on said top stone, and a cooling ring formed of complemental sections connected with said rock shafts. 25
17. An improvement in cooling devices for drawing apparatus comprising a top stone provided with a drawing opening, hangers for said top stone, rock shafts supported by said hangers, and a cooling ring formed of 30 complemental sections connected with said rock shafts.
18. An improvement in cooling devices for glass drawing apparatus comprising a top stone provided with a drawing opening, 35 hangers for said top stone, rock shafts mounted in said hangers, a cooling ring formed of complemental sections, hinge members connecting said sections to said rock shafts, and means for supplying a cooling medium to said sections through the rock shafts and hinge members. 40

In testimony whereof I have hereunto set my hand in presence of two subscribing witnesses.
